James H. Conklin, of Peekskill, N.Y.
Letters Patent, No 266. Dated Feb 19th 1850.

The schedule referred to in these Letters Patent and making part of the same.

So all whom it may concern:

Be it known that I, James H. Conklin, of the Village of Peekskill in the County of Westchester and State of New York, have invented a new and useful design and patterns for the plates of a Cook stove which are described as follows, reference being had to the annexed drawings of the same, making a part of this Specification.

Figure 1. is a representation of the front plate of the stove, with the doors closed and forming part of the design for which a patent is sought.

Figure 2. of one of the side plates of the stove, with the doors closed, and forming a part of the design for which a patent is sought: the plate on the opposite side of the stove is precisely similar to the side represented in the drawing (Fig. 2) except that on the opposite side, the upper small panel (2.) instead of being a part of the plate, is a door, with latch and hinges.

The design of the front plate (Fig. 1.) consists of a panel A. at the top, with some embossed or raised words in the middle of it, as, S. B. Sexton & Co. Md. sup. supported on each side by pilasters.

The two doors C C. have raised flowered panels, and are embellished with the designs D D. in bas relief in their centres.

The design of the side plates (Fig. 2.) consists of a border E E. em-

318-

Des. 266

- embellished with the device $\mathfrak{F}$ at the top, in bas relief: one large door $\mathfrak{G}$, with a raised flowered panel, embellished in the centre with the devices $\mathfrak{H}$, in bas relief: one small door $\mathfrak{I}$, with a raised flowered panel embellished in the centre with the device marked $\mathfrak{K}$, in bas relief, and one other small panel $\mathfrak{L}$, immediately above the small door, raised and flowered like the other panel and embellished with the device $\mathfrak{M}$, in bas relief. - On the opposite side of the stove (not represented) the panel $\mathfrak{S}$, is replaced by a door of the same form and design, as the panel $\mathfrak{S}$.

The drawings represent the outsides of the stove plates.

What I claim as my invention and desire to secure by Letters Patent is the production of the new design for stoves, as described in this specification and represented in the drawings hereto annexed at Figures 1. & 2.

Witnesses.
